CLAIM

The ornamental design for a lumbar spine fat compression shaping buttock plate, as shown and described.

DESCRIPTION

FIG. 1 is a bottom perspective view of a lumbar spine fat compression buttock plate showing my new design.

FIG. 2 is a front view of a lumbar spine fat compression shaping buttock plate.

FIG. 3 is a rear view of a lumbar spine fat compression shaping buttock plate.

FIG. 4 is a left side view of a lumbar spine fat compression shaping buttock plate.

FIG. 5 is a right side view of a lumbar spine fat compression shaping buttock plate.

FIG. 6 is a top view of a lumbar spine fat compression shaping buttock plate.

FIG. 7 is a bottom view of a lumbar spine fat compression shaping buttock plate; and,

FIG. 8 is a top perspective view of a lumbar spine fat compression shaping buttock plate.

1 Claim, 8 Drawing Sheets
